(57) **CLAIM**

The ornamental design for a cable dispensing cart, as shown and described.

DESCRIPTION

FIG. 1 is a front view of a cable dispensing cart showing our new design;

FIG. 2 is a side view of the cable dispensing cart;

FIG. 3 is an elevated perspective view of the cable dispensing cart, showing a front corner; and,

FIG. 4 is an elevated perspective view of the cable dispensing cart, showing a rear corner.

The broken lines in the figures are to show environment only and form no part of the claimed design.
